UNITED STATES PATENT OFFICE.

MICHAEL J. WALSH, OF PITTSBURG, PENNSYLVANIA, ASSIGNOR OF ONE-HALF TO FRITZ UHLENHAUT, OF PITTSBURG, PENNSYLVANIA.

RAILROAD-CROSSING FROG.

No. 902,268.

Specification of Letters Patent.

Patented Oct. 27, 1908.

Application filed July 3, 1908. Serial No. 441,856.

To all whom it may concern:

Be it known that I, MICHAEL J. WALSH, a resident of Pittsburgh, in the county of Allegheny and State of Pennsylvania, have invented a new and useful Improvement in Railroad-Crossing Frogs; and I do hereby declare the following to be a full, clear, and exact description thereof.

My invention relates to street car crossing frogs, its object being to provide a frog in which the main track is continuous while the top face of the frog is on practically the level and there is but little jump for the wheel on the auxiliary track crossing the main track.

In the ordinary street car tracks crossings are often made over the main track by tracks which have relatively little use but these tracks are generally formed where the grooves of all the tracks in the frog are made of practically the same depth and all the wheels passing over any frog have to jump the groove or recess of the track crossing the same, imparting jars to the cars and leading to large wear and breakage of the wheel tread and flanges and to large wear of the frogs themselves, even though made of especially hard metal.

By the present invention I am enabled to provide a frog with a continuous main track, so doing away with all jars on the main line while giving little or no jar to the wheels of the car crossing said track.

To these ends the invention consists in a frog having a substantially level top face and one continuous unbroken track groove, and track grooves on both sides of and leading toward but terminating short of the main groove at the crossing point thereof, such as by the employment of inclines adjacent to the main track adapted to raise the wheel to the level of the top thereof so that the wheel travels on the top face of the frog and is only required to jump over the groove of the main track.

In the accompanying drawing Figure 1 is a top or plan view of a track employing my invention; Fig. 2 is a cross section along the line of the crossing track at 2--2 Fig. 4. Fig. 3 is a perspective view of a frog embodying the invention and Fig. 4 is another plan view of a simple track crossing embodying my invention.

The frog is generally of the ordinary construction for street railways having the body portion 1, in which the ends of the different

rails are seated, for example, the rails 2, 3 of the main track and the rails 4, 5 of the crossing tracks, the ends of these different rails being seated in the main casting of body 1 of the frog in the usual way. To form the wearing surface of the frog I employ the hardened steel plate 6 which is seated and held in a regular seat formed therefor in the frog casting, being permanently held therein by Babbitt metal or the like. Extending through said frog plate 6 and in line with the groove 7 in the rails 2, 3 is the track groove 8 forming a continuous unbroken track, the rib 9 on one side and the rib 10 on the other inclosing said groove so that the wheel on the main line will travel continuously across from the main track and across said frog. As shown in the drawing the top face 11 of the frog is substantially flat on the same level, and to form the auxiliary tracks, such, for example, as the track to connect the rails 4, 5 the grooves 12, 13 extend into the frog for any desired length but terminate short of the main groove 8, for example, having the inclines 14 leading from the grooves 12, 13 up to the top of the frog, that is, the top of the rib 9 on one side and of the rib 10 on the other side of the main groove, so that the wheel in traveling along the track 3 passes into the groove 12 and is lifted gradually up onto the top face 11 of the frog and passes over the flat face thereof to the edge of the groove 8 of the main track, jumping the same and then passing down the opposite incline into the groove 13 and continuing along the track 4. These crossing tracks are arranged in any desired angle, crossing the main track either at right angles or as is usually the case, at angles of more or less acuteness.

A simple form of the invention is illustrated in the frog 16 where there is only a single crossing, the frog having the continuous groove 17 forming the main unbroken track and the crossing grooves 18, 19 leading into the frog which has the inclines 20 leading up to the flat top face 21 of the frog 16 so that the wheel can pass over the same and jump the main groove, as above described.

When the invention is in use a continuous unbroken track is provided for the main line of cars, and they pass the frog with no jar whatever, traveling in the groove of the rails and frog, providing perfectly smooth

travel, while the wheels in the track crossing the main track are subjected to no jar except for the width of the groove forming the main track, which at right angles is usually about $1\frac{3}{8}$ inches, though at other angles is, of course, somewhat increased. This jump over said groove is, however, the only shock received in passing the frog and as it is only encountered in cars traveling on tracks 5 about $1\frac{3}{8}$ inches, though at other angles is, of course, somewhat increased. This jump over said groove is, however, the only shock received in passing the frog and as it is only encountered in cars traveling on tracks 10 little used is not important. Where the tracks cross at other than a right angle it is of course evident that when the wheel is traveling on the top face of the frog and is unconfined in a groove, the corresponding 15 wheel on the other end of the axle is traveling in a groove so that the car cannot get off the track. Where the crossing is at a right angle the momentum of the car will carry both wheels over the top face of the 20 frog, as has been shown by practical use. In case the crossing track subsequently becomes the main track, it is only necessary to remove the hardened top plate of the frog and replace it with another plate having the 25 proper grooves and inclines.

By the invention I am enabled to overcome more than half of the jars encountered in an ordinary frog, and in addition to eliminating the jarring to the car, to reduce 30 the wear on the frog, largely extending its

life, and also to do away with large breakage of wheels consequent to the continual hammering blows upon the flanges and treads caused by the jumping of the grooves in the ordinary frogs.

35

What I claim is:

1. A railway frog having a substantially flat upper face, one continuous track groove extending across the same, and grooves on both sides leading toward but terminating 40 short of the main groove.

2. A railway frog having a substantially flat upper face, one continuous track groove extending across the same, and grooves on either side leading thereto but terminating 45 short of the main groove, said grooves having inclines leading to the top face of the frog.

3. A railway frog having a continuous track groove extending across the same and 50 a flat upper face leading to a cross track and providing for the travel of the wheel on the flat face of the frog in crossing the same.

In testimony whereof I the said MICHAEL J. WALSH have hereunto set my hand.

MICHAEL J. WALSH.
